Des. 225,904
Patented Jan. 9, 1973

225,904

WATERCRAFT

John L. Critcher, 144 Bosley Ave.,
Cockeysville, Md. 21030

Filed Aug. 3, 1970, Ser. No. 24,286

Term of patent 14 years

Int. Cl. D12—06

U.S. Cl. D71—1

FIG. 1

FIG. 2

FIG. 3

FIG. 4

FIG. 5

FIG. 7

FIG. 6

FIG. 8

FIG. 1 is a plan view of a watercraft according to the invention.

FIG. 2 is a side elevation of the watercraft of FIG. 1.

FIGS. 3 and 4 are front and rear elevations, respectively, of the watercraft of FIG. 1.

FIG. 5 is a plan view of a modified form of the watercraft of FIG. 1, with sails thereon.

FIG. 6 is a side elevation of a modified form of the watercraft of FIG. 1, with sails thereon.

FIGS. 7 and 8 are front and rear elevations of a modified form of the watercraft of FIG. 1, with sails thereon.

That which is claimed is:

The ornamental design for a watercraft, substantially as shown and described.
